FURFURYL N-MORPHOLINE ALKYL HALIDE
MEDICINAL PREPARATIONFred P. Nabenhauer, Somerton, Pa., assignor to
Smith, Kline & French Laboratories, Phila-
delphia, Pa., a corporation of PennsylvaniaNo Drawing. Application April 13, 1937,
Serial No. 136,527

3 Claims. (Cl. 167—65)

This invention relates to a medicinal preparation and more particularly to one adapted for oral or parenteral introduction into the human system to effect a stimulation of the para-sympathetic nervous system. Variously, the medicinal preparation in accordance with this invention, active on the para-sympathetic nervous system, will produce variously a cathartic action, a lowering of the blood pressure, etc.

10 The medicinal preparation in accordance with this invention will be a solid of high stability and of high solubility in water. It may be administered to the human system orally, in tablet form, or parenterally, in aqueous solution.

15 Broadly speaking, the medicinal preparation in accordance with this invention comprises a quaternary furfuryl alkyl ammonium halide. More specifically, the preparation in accordance with this invention may comprise a quaternary 20 difurfuryl alkyl ammonium halide, or again, specifically, a quaternary furfuryl N-morpholine alkyl halide.

25 The medicinal preparation in accordance with this invention may, for example, be an iodide, a bromide or a chloride. The alkyl group may be methyl, ethyl, propyl, isopropyl, butyl, amyl, or the like.

30 From the broad standpoint, the medicinal preparation in accordance with this invention will have the following formula:

35 in which R is an alkyl group, as methyl, ethyl, propyl, isopropyl, butyl, amyl, or the like, and in which X is a halide, as iodine, bromine, chlorine, and the like.

40 The preparation more specifically in the form of a difurfuryl alkyl ammonium halide will have the following formula:

45 in which R is an alkyl group, as methyl, ethyl, propyl, isopropyl, butyl, amyl, or the like, and X is a halide, as iodine, bromine, chlorine, or the like.

50 Again, the preparation, more specifically in the form of a quaternary furfuryl N-morpholine methiodide, will have the following general formula:

in which R is an alkyl group, as methyl, ethyl, propyl, isopropyl, butyl, amyl, or the like, and X is a halide, as iodine, bromine, chlorine, or the like.

55 By way of example of a specific preparation in accordance with this invention which has been found to be of desirable therapeutic value and, more particularly, as a stimulator for the para-sympathetic nervous system, for example, quaternary furfuryl trimethyl iodide may be used by introduction orally, in tablet form, or parenterally in aqueous solution with advantageous result.

The medicinal preparation in accordance with this invention variously may be prepared in any suitable manner. Generally speaking, a tertiary furfuryl ammonium compound is first prepared and then reacted with an alkyl halide to yield a salt of the quaternary amine.

60 The tertiary furfuryl amines may be prepared by the use of the Leuckart synthesis known to those skilled in the art and which involves the use of an aldehyde, or a ketone and a formate of an amine, or ammonia, or the formyl compound derived by dehydration of an amine formate.

The production of the preparation in accordance with this invention may be accomplished by the use of furfural and the formates of, for example, methyl amine, dimethyl amine, and morpholine, yielding, respectively, furfuryl methyl amine and difurfuryl methyl amine, furfuryl dimethyl amine and furfuryl N-morpholine amine.

65 By way of example of the preparation of difurfuryl methyl amine, 3 moles of methyl amine to 3 moles of formic acid in water are distilled until the temperature of the distillate reaches 135° C. Then 2 moles of furfural are added slowly over a period of one hour, with the distillation off of water as it forms in the reaction. Carbon dioxide and methyl amine are also produced during the reaction, which takes place in two stages, as follows:

70 After the furfural has all been added and the reaction has subsided, the residue is cooled, diluted with water, made strongly alkaline and distilled until all volatile substances are removed. The distillate is then made acid with formic acid and distilled with steam as long as

non-basic substances are carried over by the steam. The residue is then made strongly basic with caustic soda and the volatile amines again distilled with steam. The distillate is then treated with strong alkali and then extracted with ether to extract the mixture of bases. The extract is dried by the addition of caustic potash, the ether removed and the residual amines separated by distillation.

10 The two bases obtained by this procedure are furfuryl methyl amine, boiling at 145-150° C., and difurfuryl methyl amine, boiling at 237-238° C.

For production of the furfuryl dimethyl amines, 5 moles of dimethyl amine to 5 moles of formic acid and water are distilled to 135° C. to distill off the water. To the remaining liquid, consisting for the most part of the formyl derivative of dimethyl amine, 1 mole of furfural mixed with 1 mole of formic acid is added with heating, the temperature being maintained at 150-170° C. until the reaction is complete. The reaction mix is then distilled into a receiver. The course of this reaction may be illustrated as follows:

30 The formic acid used in the above reaction functions to react with the dimethyl amine liberated in the reaction.

The final distillate obtained is unchanged dimethyl amide of formic acid, formic acid and furfuryl dimethyl amine. The furfuryl dimethyl amine is separated as described above with reference to the separation of furfuryl methyl amine; i. e. by steam distillation from acid solution and then from alkaline solution, treating the distillate with caustic soda to render it strongly alkaline, extracting the amine with ether, drying and distilling. The furfuryl dimethyl amine boils over the same range as the mono methyl derivative, 145-150° C.

45 Furfuryl morpholine amine may be made up in the manner described above, using 5 moles of morpholine and 5 moles of formic acid and reacting with one mole of furfural.

In carrying out the reaction and separating the final product the procedure described above is 50 followed.

For the preparation of the quaternary com-

pounds, the tertiary amine is dissolved in dry benzene and to the solution is added one equivalent of an alkyl halide with inducement of crystallization of the quaternary salt as, for example, by scratching the side of the vessel containing the reaction mix, or seeding with a small quantity of the crystalline quaternary salt.

5 Where pure amine and pure alkyl halide in dry benzene are used, the quaternary salt will separate out in pure form after a shorter or 10 longer period, depending on the alkyl halide used.

As has been indicated above, the medicinal preparation prepared in accordance with this invention will be found to possess excellent therapeutic properties, more particularly with respect to the para-sympathetic nervous system. The preparation is a salt of high stability and high water solubility and lends itself to introduction into the human system orally, for example, in tablet form, or parenterally in aqueous solution.

What I claim and desire to protect by Letters Patent is:

1. A medicinal preparation for effecting stimulation of the para-sympathetic nervous system comprising a furfuryl N-morpholine alkyl-halide having the following formula:

30 in which R is an alkyl group from the group consisting of methyl, ethyl, propyl, isopropyl, butyl and amyl groups and X is a halide.

2. A medicinal preparation for effecting stimulation of the para-sympathetic nervous system comprising a furfuryl N-morpholine alkyl-halide having the following formula:

40 in which R is an alkyl group from the group consisting of methyl, ethyl, propyl, isopropyl, butyl and amyl groups.

3. A medicinal preparation for effecting stimulation of the para-sympathetic nervous system comprising furfuryl N-morpholine methiodide. 45

FRED P. NABENHAUER. 50
